UNITED STATES PATENT OFFICE.

ATTILIO B. PIATTI, OF NEW YORK, N. Y.

HOD-ELEVATOR.

SPECIFICATION forming part of Letters Patent No. 271,113, dated January 23, 1883.
Application filed October 12, 1882. (No model.)

To all whom it may concern:

Be it known that I, ATTILIO B. PIATTI, of New York city, have invented certain new and useful Improvements in Hod-Elevators, of which the following is a specification.

My invention relates to that class of elevators employed by builders to raise hods of bricks and mortar or other building material within buildings in course of erection. Two types of elevators are in use for this purpose, in one of which an endless ladder-chain is employed, passing around a windlass at the bottom and over pulleys at the top, and the hods are provided with hooks, so as to be hooked directly onto the links or rounds of the ladder-chain, and thus raised by the motion of the chain. In the other type a car or platform is used which moves in fixed guides and is suspended from a hoisting-cable which extends to a winding-drum or hoisting-engine, and the hods are placed directly on the car. My invention applies to this latter form of hod-elevator, and it aims to so construct the parts as will support the hods firmly and yet admit of their very quick and easy placement on and removal from the car, and also to insure the smooth and easy motion of the car in the guides.

To these ends my improvements may be stated to consist in brace rods or rails rising from the car in position to admit the handles of the hods between them, while the hod reclines against the top cross-bar of the car in cups or sockets near the outer edges of the car, between said rails, to receive the ends of the reclining-hod handles; also, in certain arrangement of guide-rollers and slides at top and bottom of the car, whereby a smooth, easy movement of the car in the guides is insured, notwithstanding the fact that the car may be tilted in the guides or bear unevenly therein, due to a greater weight on one side than the other, as hereinafter fully set forth.

Figure 1 of the annexed drawings presents a front elevation of my improved hod-elevator, showing hods placed thereon. Fig. 2 is a cross-section of the same on $x x$. Fig. 3 is a sectional plan on line $y y$ of Fig. 1. Fig. 4 is a vertical section through the upright frame-beam of the car at the guide-roller and slide. Fig. 5 is an inner view of the roller and its box or bearing.

In the drawings, $a a$ indicate the fixed ways or guides in which the elevator-car B moves. $e d$ indicate the base or platform of the car, which is preferably formed of a strong marginal wooden frame, c , joined transversely by a number of cross slats or beams, d , which are placed at such intervals as to leave slots or openings of about their own width, which allow any mortar overflowing or slopping over from the hods to fall through to the bottom of the shaft, and thus prevent accumulations on the platform.

From the ends of the platform strong upright beams arise in line with the guides a , and of about equal width, as seen in Fig. 2, and these uprights are connected near the top by the cross-beam or head-piece f of the car, to the center of which the hoisting-cable g connects, as shown in Figs. 1 and 3. The cable does not connect directly to the head-piece f , but to an iron rod, h , which has an eye or socket on its upper end to receive the end of the cable, and which passes down through the center of the cross-beam, and is threaded to receive the nuts $i i$, which embrace the beam between them, and thus firmly connect the rod with the beam, as seen in Figs. 1 and 3. The rod h is reduced in diameter below the head-beam f , and is thence continued down through the central bar, d , in the platform, and its extremity is threaded to receive a nut, j , which bears upon the under side of the platform, so that the rod thus makes a firm suspensory-connection from the cable with both the top and bottom of the car. The reduction in the diameter of the lower portion of the rods is for the purpose of readily admitting the nuts, as will be understood.

Now, the car is made preferably of such a size as will admit two hods on each side of the head-beam, as seen in Figs. 1 and 3, the design being such that the hods, when placed on the car, will rest against the head-beam, so as to recline thereagainst by their own gravity, and at a sufficient inward inclination to render their position quite firm and stable, as will be understood from Fig. 3. The degree of inward inclination of the hods will be determined by the width of the platform, and in order to give the hods the greatest available degree of inclination the ends of the hod-handles are sup-

ported at the extreme edge of the platform in 5 depressed sockets or cups *k* *k*, sunk into the marginal frame of the platform, as shown best in Figs. 2 and 3. The cups *k* are preferably made of cast-iron, suitably screwed or fastened in the platform, with their front and side walls perpendicular, to form stops to receive and restrain the ends of the hod-handles, and with their bottoms inclined upwardly and inwardly, 10 so that when the hod-handle is inserted in the cup it will at once slide down the incline against the upright side of the cup, and thus allow the hod to recline firmly against the head-beam at its utmost inclination, while firmly holding the hod on the platform at this inclination, as will be understood. The cups *k* thus firmly support the vertical strain of the hods, while the head-beam *f* supports the lateral strain thereof, due to their inclination 15 against the same, which being equal on each side of the head-beam, there hence exists no tendency to force the beam one way or the other.

Brackets *l* project from the middle of the 20 head-beam on each side between the hods, and also from the uprights *b* *b* on each side at the outer ends of the hods, and thus effectually prevent the longitudinal displacement of the hods, as will be readily appreciated, while the 25 straight vertical sides of the cups *k* prevent the possible displacement of the hod-handles at the base, thus rendering the arrangement of the hods very secure. The position of the hods is still further secured by guard-rails or 30 bails *m* *m*, which rise from the platform on either side of the hod-handles, and are braced at the middle by a brace-rod, *n*, which extends longitudinally across the center of the car at one side of the central rod, *h*, and is fastened 35 at each end to the uprights *b* of the car, as fully shown in Figs. 1 and 3.

The rails *m* and brace-rod *n* may be formed of iron pipe and pipe-fittings, or of rod-iron forged into the proper form, and the ends of 40 the rails are of course firmly secured to the margins of the platform on each side of the cups *k*, as best shown in Figs. 1 and 2.

It will be noted that the rails are arranged 45 in pairs at each set of cups, the rails of each pair being sufficiently separated to readily admit the hod-handle between them, and the rails rise to a height above the platform, preferably from one-half to two-thirds the height 50 of the handles, so that the exposed part of the handles above the rails admits of being readily grasped by the hand in placing the hods on the car or removing them therefrom, as will be understood. It may therefore be now seen that the constructions for receiving, holding, 55 and steadying the hod on the car are very simple and secure, without requiring any addition to the hods or any special construction thereof, and are of such a nature that the hods can be placed on the car or removed therefrom 60 very easily and quickly without detaching any fastenings, which greatly facilitates the work

of supplying the building materials, and reduces, as far as possible, the chances of loss or accident in the handling of the hods.

Referring to Fig. 1, it will be noted that the 70 uprights of the car project some distance above the head-beam *f*, and near the top of these uprights rollers *o* *o* are mounted thereon and project through openings therein and bear upon the guides *a* *a*. A second set of rollers 75 *o* *o* are mounted in a similar manner in the lower ends of the uprights and bear upon the guides near the base of the car. This second set of rollers is preferably placed just above the platform; but they may be placed below 80 the platform if the uprights *b* project below the same, as will be understood. These rollers, as may now be seen, in bearing upon the guides, prevent the uprights or the platform from making direct contact therewith, and thus form a 85 rolling-bearing between the car and the guides, which avoids friction and insures a smooth and easy motion of the car and greatly reduces the wear of the guides. It may also be noted that as these rollers are placed at nearly the extreme 90 top and bottom of the car, hence, no matter how much the car might tend to tilt in the guides by being loaded heavier on one end than the other, two rollers at diagonally-opposite corners will always bear upon the guides and 95 prevent any sliding contact of the car therewith, thereby insuring a smooth and easy motion, even when the car is unequally loaded and slightly tilted, and thus avoiding the jerky motion which commonly occurs under the same 100 conditions with the car as heretofore equipped, and which tends to displace the hods or spill the contents.

In addition to the rollers *o*, clasps or slides 105 *p* *p* project from the uprights *b* upon each side of the guides, and thus prevent the lateral motion of the car in the guides, as will be understood. Instead of these clasps, rollers similar to the rollers *o* may be employed; but the clasps 110 are deemed preferable. These clasps *p* are preferably formed of cast-iron screwed to the outer face of the uprights *b*, and they are preferably located on the uprights at top and bottom, coincident with the rollers *o* *o*, the peripheries of which project through an opening in 115 the base-plate of the clasps and bear upon the guides at the middle of the clasps, as best shown in Figs. 1 and 4, while the guide-rollers are 120 journaled in a metal plate which is screwed to the inside of the upright coincident with the base-plate of the clasps, as also shown in Figs. 1, 4, and 5. The construction and attachment of the rollers and clasps are thus very simple and strong.

I do not wish it to be inferred that either clasps 125 or rollers on the car are new in themselves; but usually the rollers have been located at or near the middle of the car, or at one end only, and not at the extreme top and bottom of the same with coincident clasps, as in my case, so that 130 in the former arrangements the tilting of the car would cause either top or bottom to make

sliding contact with the guides, and thus produce great friction, which obviously cannot occur in my arrangement. I would also remark that clasps are of course commonly used to embrace the guides, and at top and bottom of the car; but they have not been used with rollers in coincident position, as in my case, which is a much more simple and compact arrangement, and is also stronger, as the clasp serves to strengthen and brace the uprights where they are perforated to admit the rollers.

What I claim is—

1. In a hod-elevator, the cups or sockets *k*, affixed at or near the margins of the platform, to receive the base ends of the hod-handles and sustain the weight of the same vertically, substantially as herein set forth.

2. The combination, with the car of a hod-elevator adapted to receive the hods in an upright position, reclining inwardly against the head or cross-beam of the car, of cups or sockets fixed at or near the outer edge of the platform to vertically receive and support the base ends of the hod-handles, and suitable stops or guards to prevent the endwise displacement of the hods, substantially as herein shown and described.

3. The combination, with the platform and frame of a hod-elevator adapted to receive the hod in an inwardly-reclining position, and with stops to prevent the longitudinal displacement of the hods, of the supporting cups or sockets *k* *k*, affixed at or near the margin of the platform, and formed with upright front and side walls and an inclined base, substantially as and for the purpose set forth.

4. The combination, with the car of a hod-elevator, with means for supporting the hod in an upright or reclining position thereon, of guard-rails arranged on each side of the hod-handles, substantially as and for the purpose set forth.

5. The combination, with the car of a hod-elevator adapted to receive the hods in an upright position, reclining inwardly against the head-beam, of cups or sockets *k*, fixed at or near the outer edge of the platform, and the guard-rails *m* *m* on each side thereof, substantially as and for the purpose set forth.

6. The combination, with the car of a hod-elevator, with means to receive and support the ends of hod-handles and means to support the top of the hod, of the guard-rails *m* *m* and brace-rod *n*, secured to each other and to the car, substantially as and for the purpose set forth.

7. The combination, with the car and its guides, of the rollers *o* *o*, journaled at the top and bottom of the car and bearing on the guides, with the clasps *p* *p*, projecting from the car coincident with the rollers, and embracing the guides on each side of the rollers, substantially as and for the purpose set forth.

8. The combination, with the car, of the rollers *o*, journaled in a base-plate affixed on the inside of the uprights of the car and projecting through an opening therein, with the metallic clasps *p* *p*, embracing the guides on each side of the roller, and formed with a base-plate which is secured to the outer face of the upright over or around the opening in which the roller works, substantially as herein shown and described.

9. The combination, with the platform, uprights, and head-beam of the car, of the central suspensory screw-rod, *h*, passing through the head-beam and through the platform, and provided with nuts *i* *i*, embracing the head-beam, and a nut, *j*, underlying the platform, substantially as herein shown and described.

ATTILIO B. PIATTI.
